His Attorney.

UNITED STATES PATENT OFFICE.

GEORGE M. HOLLOWBACK, OF LEWISTOWN, MONTANA.

OVEN OR FURNACE.

1,331,644.

Specification of Letters Patent. Patented Feb. 24, 1920.

Application filed July 11, 1918. Serial No. 244,466.

To all whom it may concern:

Be it known that I, GEORGE M. HOLLOWBACK, a citizen of the United States, residing at Lewistown, in the county of Fergus and 5 State of Montana, have invented new and useful Improvements in Ovens or Furnaces, of which the following is a specification.

This invention relates to ovens or furnaces, and it has for its object to provide an 10 oven or furnace, for use in connection with dental and other operations, and whereby an object or work of any kind may be subjected to heat at a predetermined temperature, for a predetermined period of time. It will be 15 obvious that an oven or furnace so organized is capable of use for a wide range of purposes, and throughout a wide range of the arts, and it is particularly useful for subjecting to heat, in the art of dentistry, flasks 20 containing wax models invested in initially plastic material, and from which investment such wax or the like is to be burnt out to leave the mold in which inlays, crowns, bridges and the like, may be cast. The invention 25 has for further objects the provision of improved ovens or furnaces of the general character stated, which will be superior in point of relative simplicity and inexpensiveness of construction, taken in connection 30 with reliability, and accuracy and positiveness in operation, automatic performance, convenience in use and adjustment, compactness in form and durability, and which will be generally superior in efficiency and 35 serviceability.

With the above and other objects in view, the invention consists in the novel and useful provision, formation, construction, combination, association, and relative arrangement 40 of parts, members and features, all as hereinafter described, shown in the drawing, and finally pointed out in claims.

In the drawing:

Figure 1 is a central longitudinal sectional view, partly in elevation, of oven or furnace mechanism, constructed and organized to embody the invention;

Fig. 2 is a detail view of parts of the pendulum and associated parts;

Fig. 3 is a similar view of the work supporting carriage;

Fig. 4 is a plan view of the adjustable end standard;

Fig. 5 is a detail view of the electric make and break device which is actuated by the pendulum;

Fig. 6 is a detail view of the connection between the ratchet wheel and the worm shaft;

Fig. 7 is an enlarged detail view, partially 60 in section, of the bearing at one end of the threaded shaft.

Corresponding parts in all the figures are designated by the same reference characters.

Referring with particularity to the drawing, the improved furnace or oven mechanism therein shown comprises in the main an oven or furnace working chamber A which is provided in a casing 7 having throughout a heat insulating lining, as indicated at 8, on its top closure 9, which is detachable, and through which projects a temperature-indicating device, such as a thermometer h with its bulb and a mercury bath. The casing 7 is open at its ends, and 70 ranging lengthwise thereof through the chamber A is a threaded shaft b for feeding or advancing through such chamber A an object, article or work C to be subjected to heat emanating from heat producing means 75 10 disposed beneath the bottom member 7^a of the casing 7. Such heat producing means are indicated as an electrical resistance coil in circuit with which is a thermostatic device E disposed within the chamber A, and 80 15 adapted to cause the intermittent energization of the coil 10 so as to maintain a constant temperature within the chamber A. F designates a source of electrical energy for the coil 10 and also for the work advancing means. In the present construction 85 the threaded shaft b is intermittently rotated to advance the work C which is supported by a traveler or carriage 12 having a threaded knuckle 13 which interengages 90 with the threads of the member or shaft b, so that the traveler 12 moves lengthwise 95 through the chamber A when the shaft is rotated. The means for rotating the shaft b comprises a ratchet wheel 14 loose upon a 100 stub shaft 15, there being a pendulum 16 fulcrumed upon such stub shaft, as at 17, and carrying a dog 18 adapted to intermittently rotate the ratchet wheel 14 as the 105 pendulum is oscillated; such pendulum being actuated by an electro-magnet 19 energized from the source of electrical energy F, a transformer f being included in the circuit between such source of electrical energy and the electro-magnet, for the purpose of reducing the voltage. Included within such 110 electrical circuit supplying the electro-mag-

net 19, is a make and break device, which consists of a contact terminal 20 adapted to be intermittently engaged by a sliding contact device 21 mounted in a suitable slide-way 22, and having spaced actuating pins 23 arranged to be alternately engaged by an insulated portion 24 of the pendulum 16. The end of the shaft *b* remote from the ratchet wheel 14 has the pivot bearing 11, 10 the same co-acting with a stub shaft 25, supported by a standard 26. The other end of such shaft *b* has a pivot bearing connection as at 27 with the stub shaft 15; and a collar 28 fast upon the shaft *b* at the latter end is 15 connected operatively with the ratchet wheel 14 by angular arms 29, so that the shaft *b* turns with the ratchet wheel.

The arms 29 are loosely received within 20 openings 30 in the ratchet wheel 14, and the point bearings at 11 and 27 may be tightened or loosened by adjustment of the standard 26 with its stub shaft 25, such standard having a slotted foot 31 through which passes a threaded bolt 32 fixed in a base block 33, 25 and having a thumb nut 34 whereby the foot 31 may be bound down in position of adjustment.

The operation, method of use and advantages of the improved oven or furnace mechanism constituting the invention, will be 30 readily understood, with all of its adaptabilities to varying kinds and conditions and characters of use and service, by those skilled in the arts, by reason of the foregoing description and the accompanying drawing and the following statement:

The work is placed upon the traveler or carrier 12, and such work may consist of a dental flask, having in its initially plastic 40 investment a model of wax for inlay, bridge, crown or other dental work. This work is caused to enter the chamber A at one end thereof and travel through the chamber by rotation of the shaft *b* due to actuation by 45 the ratchet wheel 14. The pendulum 16 which intermittently rotates the ratchet wheel is oscillated under influence of the electro-magnet 19, which co-acts with an armature 19^a upon the pendulum, the electro-magnet being intermittently energized 50 and de-energized through the action of the circuit maker and breaker. Thus the ratchet wheel 14 is intermittently turned by the dog 18 and the shaft *b* intermittently rotated to 55 advance the work C step by step through the chamber A, at a rate of speed predetermined and predicated upon the operation of the ratchet wheel and pendulum. The temperature of the heat producing means D 60 is likewise predetermined, and may be maintained by the thermostatic element E or voluntarily through a suitable switch or controlling member in accordance with readings of the thermometer *h*. The length of 65 the chamber A is a definite quantity, and

thus, inter-calculating all of these factors of chamber length, speed of carriage movement and degree of heat, the total application of heat to the work may be definitely predetermined and controlled.

70 Thus, the work C may issue from the chamber A accurately and completely affected by heat as predetermined, as for instance, with the wax model in the mold in the dental flask entirely eliminated by heat action. 75 The dentist or operator or attendant may thus maintain a sequence of heating performances with respect to a plurality of specimens of work, each carrier 12 being open at one side so that it may be readily 80 placed upon or removed from the shaft *b*. It is evident that the heat produced by the coil 10 may be varied by changing the resistance thereof, or the amount of electrical energy supplied thereto, and the rate of 85 travel of the work through the chamber A may be varied by substituting shafts *b* of varying pitches of thread or this result may be accomplished by varying the stroke of the pendulum.

90 It is obvious that the use of mechanism or apparatus of the character disclosed makes for accuracy in performance, combined with convenience in control and automatic performance, and that many variations or modifications and alterations and substitutions may be made, with respect to the specific apparatus pictured and described, in adapting the invention to varying conditions of use and service, without 95 departing from the true spirit of the invention.

100 Having thus disclosed my invention, I claim and desire to secure by Letters Patent:

1. A device of the character described, including a heating chamber, a work supporting carriage mounted to move through the chamber, an oscillating device, means actuated by the oscillating device for advancing the carriage through the chamber, and an 110 electro-magnet together with a make and break device associated with the oscillating member for actuating the same.

115 2. Improvements of the character disclosed, comprising a heating chamber, a threaded shaft ranging through said heating chamber, a carriage adapted to traverse said shaft, and means for moving said carriage lengthwise of said shaft through said heating chamber; said latter means comprising an oscillating element, a rotating element operatively connected with said shaft, and means for converting the movements of said oscillating element into step by step rotation of said rotating element.

120 3. Improvements of the character disclosed, comprising a heating chamber, a threaded shaft ranging through said heating chamber, a carriage adapted to traverse said shaft, and means for moving said carriage 125

lengthwise of said shaft through said heating chamber; said means comprising an oscillating element, a rotating element for said shaft and receiving its actuation from said oscillating element, and electro-magnetic means for operating said oscillating element.

4. Improvements of the character disclosed, comprising a heating chamber, a threaded shaft ranging through said heating chamber, a carriage adapted to traverse said shaft, and means for moving said carriage lengthwise of said shaft through said heating chamber; said means comprising an oscillating element, a rotating element for said shaft and actuated by said oscillating element, an electro-magnet, and a make and break device in circuit with said electro-magnet and controlled by said oscillating element, said oscillating element having an armature for acting responsive to energization of said electro-magnet; said make and break device comprising a fixed contact device and a sliding contact device with the latter of which said oscillating element is intermittently engaged.

5. Improvements of the character disclosed, comprising a heating chamber, a

threaded shaft ranging through said heating chamber, a carriage adapted to traverse said shaft, and means for moving said carriage lengthwise of said shaft through said heating chamber; said means comprising an oscillating element, a rotating element for said shaft and actuated by said oscillating element, an electro-magnet, and a make and break device in circuit with said electro-magnet and controlled by said oscillating element, said oscillating element having an armature for acting responsive to energization of said electro-magnet; said make and break device comprising a fixed contact device and a sliding contact device with the latter of which said oscillating element is intermittently engaged.

In testimony whereof, I have signed my name to this specification in the presence of two subscribing witnesses.

GEORGE M. HOLLENBACK.
